PIPE HOLDER

Jerome N. Felten, 3517 E. 26th St.,
Minneapolis, Minn. 55406

Filed Nov. 26, 1968, Ser. No. 14,665

Term of patent 14 years

Int. Cl. D27—02

U.S. Cl. D85—8

FIG. 1

FIG. 3

FIG. 4

FIG. 5

FIG. 2

The bottom not shown is substantially plain.

Portions of the drawing figures have been stippled to indicate contrast in appearance.

I claim:

The ornamental design for a pipe holder, substantially as shown and described.
